Primary Examiner — Mitchell I. Siegel

(57) **CLAIM**

The ornamental design for a golf club head, as shown and described.

DESCRIPTION

FIG. 1 is a top perspective view of a golf club head according to a first embodiment;

FIG. 2 is a rear perspective view of the golf club head of FIG. 1;

FIG. 3 is a front elevational view of the golf club head of FIG. 1;

FIG. 4 is a rear elevational view of the golf club head of FIG. 1;

FIG. 5 is a top view of the golf club head of FIG. 1;

FIG. 6 is a bottom view of the golf club head of FIG. 1;

FIG. 7 is a left side view of the golf club head of FIG. 1;

FIG. 8 is a right side view of the golf club head of FIG. 1;

FIG. 9 is a top perspective view of a golf club head according to a second embodiment;

FIG. 10 is a rear perspective view of the golf club head of FIG. 9;

FIG. 11 is a front elevational view of the golf club head of FIG. 9;

FIG. 12 is a rear elevational view of the golf club head of FIG. 9;

FIG. 13 is a top view of the golf club head of FIG. 9;

FIG. 14 is a bottom view of the golf club head of FIG. 9;

FIG. 15 is a left side view of the golf club head of FIG. 9;

FIG. 16 is a right side view of the golf club head of FIG. 9;

FIG. 17 is a top perspective view of a golf club head according to a third embodiment;

FIG. 18 is a rear perspective view of the golf club head of FIG. 17;

FIG. 19 is a front elevational view of the golf club head of FIG. 17;

FIG. 20 is a rear elevational view of the golf club head of FIG. 17;

FIG. 21 is a top view of the golf club head of FIG. 17;

FIG. 22 is a bottom view of the golf club head of FIG. 17;

FIG. 23 is a left side view of the golf club head of FIG. 17;

and,

FIG. 24 is a right side view of the golf club head of FIG. 17.

The broken lines shown on the drawings form no part of the

claimed design. The stippled areas of FIGS. 9-16 are shown

to indicate a contrasting color.

1 Claim, 12 Drawing Sheets
